INTERLOCKING SYSTEM FOR RAILROADS

Sedgwick N. Wight, Rochester, N. Y., assignor to
General Railway Signal Company, Rochester,
N. Y.

Application May 28, 1937, Serial No. 145,337

13 Claims. (Cl. 246—134)

This invention relates to interlocking systems for railroads, and more particularly pertains to an interlocking system which can be operated by either automatic traffic conditions or manual manipulation of control means.

A provision is made by this invention whereby an interlocking system can be operated automatically by trains entering approach sections; or upon reversing a switch in the control office, the interlocking system can be manually controlled from a central office by control buttons for the entrance and exit ends of the several routes of the track layout. The present invention employs features disclosed in my prior application Ser. No. 721,696 filed April 21, 1934, but no claims are made herein to any invention disclosed in my said prior application.

A system of this character is particularly useful at those interlocking plants where traffic is generally light, but at certain times becomes so dense as to require the control of the plant by an operator.

One of the objects of the present invention is to provide a system of this type so organized as to be particularly adaptable to the entrance-exit type of manipulation as well as adaptable to automatic control by train presence, and to have as much of the apparatus as possible common to both sets of control means.

Other objects, purposes and characteristic features of the present invention will be in part obvious from the accompanying drawings and in part pointed out as the description of the invention progresses.

The accompanying drawings show one embodiment of the present invention as applied to a railway track layout in which each track is signalled for traffic in both directions.

Fig. 1 shows the apparatus located in the control office.

Fig. 2 shows the apparatus located at the field track layout.

With reference to Fig. 2, a diverging track 17 is illustrated as having a track circuit 4 and connected to a main track 18 by means of the track switch TS. Track 18 is divided into track circuits 2, 7 and 8, and is crossed by track 19 which is divided into track circuits 5 and 6 as well as having a section in common with track circuit 7.

Each of these track circuits is provided with the usual track relay T and a track battery. The track relays T are indicated as associated with their respective track sections by their distinguishing preceding numerals.

The track layout is provided with signals of

the color light type for governing traffic through the interlocking plant in both directions on each track. Signal 10A governs east-bound traffic over track 18, while signal 11 governs west-bound traffic. Signals 10B and 12 govern traffic over tracks 17 and 18 by way of the track switch TS, signal 10B governing east-bound traffic and signal 12 governing west-bound traffic. Signals 13 and 14 govern traffic over track 19, signal 13 governing south-bound traffic and signal 14 governing north-bound traffic.

Each signal has a stick relay S associated therewith to prevent that signal from automatically clearing when a train is leaving the interlocking plant. A push button PB is provided for each stick relay to release its associated signal for clearing in the event a leaving train desires to reverse its direction and reenter the plant.

The switch machine SM provides for the power operation of the track switch TS, and is controlled by a two position polar relay Z in a similar manner as the switch machine SM in the Patent No. 1,975,137 dated October 2, 1934, is controlled by its lever SML. The switch machine SM may be of any suitable type, such as shown in the patent to W. K. Howe, Patent No. 1,466,903, dated September 4, 1923.

A polar neutral relay WP is associated with the switch machine SM and the track switch TS for repeating the position of the track switch points in correspondence with the operating mechanism of the switch machine SM, the relay being energized with one polarity when the track switch is in its normal position and locked, and energized with the other polarity when the track switch is in its reverse position and locked. The relay WP is deenergized during the operation of the track switch and also at such other times as the track switch points are unlocked.

The present invention contemplates that suitable approach and detector locking is employed to protect against the operation of the track switch TS while it is unsafe for such operation. Thus, a lock relay L has been shown as interrupting the control for the switch machine SM when it is deenergized, and it is deenergized whenever a signal is cleared to allow the passage of traffic over the track switch TS and whenever the track section 7 is occupied by a train. When approach locking with time release is employed, the relay L is not reenergized until after a predetermined time has elapsed following the putting to stop of the governing signal.

A push-button 10—12PB is located near signal 55

10 and is operated by a trainman, while the system is set for automatic control and a train is standing on approach section 2, to set up a route over track switch TS in a reverse position 5 between signals 10 and 12.

10 Referring to Fig. 1, the control machine is provided with a control panel upon which a track diagram is located corresponding to the actual track layout in the field. Entrance buttons N and exit buttons X are located on the control panel for the ends of the routes, while indicators TK advise the operator of the conditions of occupancy for their respective track sections as shown in my prior application Ser. No. 69,905 filed 15 March 20, 1936. A signal indicator SK is located in the center of each of the entrance buttons N, and is illuminated when its corresponding signal is cleared. The control of these indicators TK and SK has not been shown, but may be as shown 20 in my above mentioned prior application.

25 Route relays 10-11, 10-12 and 13-14 are of the polarized neutral type and are used in selecting and interlocking the several routes under both manual and automatic conditions of operation.

30 Relays AR and ASR are used in setting up a route for a train when the interlocking is under automatic operation.

35 A switch SW is used in transferring the interlocking system from manual to automatic operation when actuated to its opposite positions M and A respectively.

40 For the purpose of simplifying the illustration and facilitating in the explanation, the various parts and circuits constituting the embodiment of the invention have been shown diagrammatically and certain conventional illustrations have been employed, the drawings having been made more with the purpose of making it easy to understand the principles and mode of operation, than with the idea of illustrating the specific 45 construction and the arrangement of parts that would be employed in practice. Thus, the various relays and buttons with their contacts are illustrated in a conventional manner, and symbols are used to indicate connections to the terminals of batteries, or other sources of electric current, instead of showing all of the wiring connections to these terminals.

50 The symbols (+) and (−) are employed to indicate the positive and negative terminals respectively of suitable batteries, or other sources of direct current; and the circuits with which these symbols are used always have current flowing in the same direction.

55 It is believed the nature of the invention, its advantages and characteristic features can be best understood with further description being set forth from the standpoint of operation.

60 Operation

65 Under normal conditions with the track sections unoccupied all of the track relays are energized and the track switch TS is in either a normal or a reverse position depending upon the last route set up. The track occupancy indicator lamps TK, and signal indicator lamps SK on the control panel are normally deenergized, thereby giving a so-called "dark board."

70 Assuming an operator wishes to control the interlocking plant by means of the entrance and exit buttons located on the control panel, he must first operate the transfer switch SW to position M, doing so only at times when the indicator lamps on the control panel indicate that

no signals have been cleared by reason of the presence of trains on the approach sections.

Having thus positioned the transfer switch SW, let us assume that a train is approaching signal 10 on track 18 to a position where the track relay 2T is dropped away causing indicator 2TK to be illuminated. This advises the operator of the presence of a train. The operator now proceeds to set up a route for the train on track 18 by first turning the entrance button 10N in a clockwise direction and then pressing the exit button for the end of the route where he wishes the train to leave the interlocking plant. Assuming he wants the train to leave on track 18, he presses the exit button 11X. 15

A circuit is now closed for energizing route relay 10-11 from (+), through a circuit including contact 20 of switch SW, contact 21 of entrance button 10N, winding of route relay 10-11, back contact 22 of route relay 13-14, 20 back contact 23 of route relay 10-12, back contact 41 of entrance button 11N, back contact 24 of exit button 11X, contact 25 of switch SW, to (−). When relay 10-11 picks up, a stick circuit is closed from (+) through a circuit including contact 20 of switch SW, front contact 21 of entrance button 10N, winding of route relay 13-14, back contact 22 of route relay 10-12, right contact 26 of route relay 10-11, front 30 contact 27 of relay 10-11, contact 25 of switch SW, to (−).

35 The route relay 10-11 being picked up closes a circuit for energizing the switch control relay Z from (+), through a circuit including front contact 28 of relay 10-11, lower winding of relay Z, to (−). The relay Z is a polar relay with two separate windings differentially connected so that energization of its lower winding causes its contacts to assume a polar position which will cause the switch machine SM to operate to its normal position, while energization of its upper winding causes its contacts to be operated to opposite positions to cause the reverse operation of the switch machine SM. The relay Z 40 controls the switch machine SM by a circuit heretofore referred to as being shown more in detail in the prior Patent No. 1,975,137, and mentioned as including a selection through the front contact of a lock relay L, the control of which 45 lock relay should necessarily include such detector and approach locking as the particular condition may require.

50 Each signal has been shown as having green and red lamps controlled respectively by the front and back contacts of a signal control relay G (not shown). The control for each signal control relay G (not shown) has been indicated by dotted lines as including front and polar selections of the proper route relay, and 55 a front contact of the detector track relay.

60 Assuming that the track switch TS has properly responded to the relay Z so that relay WP indicates the switch to be in a normal locked position, then a circuit is closed for the control of signal 10A from (+), through a circuit including front contact 29 of relay WP, polar contact 30 of relay WP in a right hand position, front contact 31 of route relay 10-11, polar contact 32 of relay 10-11 in a right hand position, a front contact 77 on track relay 7T, to the signal control relay (not shown), the energization of which clears signal 10A. 65

70 The fact that signal 10A has been cleared is indicated to the operator in the control office 75

by the illumination of the lamp 10SK located within the button 10N on the control panel, thus indicating that the route has been completely set up.

When the train accepts the signal 10A, the track indicator lamp 7TK on the control panel is illuminated to inform the operator that the train has accepted the signal, at which time the operator may return his entrance button 10N to its normal position.

However, the dropping of the detector track 7T had already opened the control circuit of signal 10A at open front contact 17 causing the green lamp to be extinguished and the red lamp 15 illuminated.

The operator may at this time, if he so desires, operate the entrance-exit control buttons for setting up another route. The signal controlling the new route, however, will not clear 20 until the detector track section has been unoccupied, and until the switch TS has been operated to its proper position and locked, if the new route includes that track switch.

Assuming the train to have left the interlocking plant and another train to have entered approach section 2 on the same track, the operator may set up a route for the approaching train over the track switch TS in its reverse position to track 17 by first turning button 10N 30 in a clockwise direction and pressing exit button 12X.

The pressing of button 12X closes a circuit for energizing route relay 10-12 from (+), through a circuit including contact 20 of switch SW in position M, front contact 21 of button 10N, back contact 33 of relay 10-11, back contact 34 of relay 13-14, winding of relay 10-12, back contact 48 of button 12N, back contact 35 of button 12X, contact 25 of switch SW in position M, to (-). The picking up of route relay 10-12 closes its stick circuit from (+), through a circuit including contact 20 of switch SW in position M, front contact 21 of button 10N, back contact 33 of relay 10-11, back contact 34 of relay 13-14, winding of relay 10-12, polar contact 36 of relay 10-12 in a right hand position, front contact 37 of relay 10-12, contact 25 of switch SW in position M, to (-).

The relay 10-12 now effects the operation of the track switch TS to its reverse position by energizing the relay Z to its left hand polar position by a circuit closed from (+), through a circuit including front contact 16 of relay 10-12, upper winding of relay Z, to (-). The polar contacts of relay Z in their left hand positions close a circuit (not shown) for reversing the track switch TS.

With the track switch TS in its reverse position and locked, a circuit is closed for clearing signal 10B from (+), through a circuit including front contact 29 of relay WP, polar contact 30 of relay WP in a left hand dotted position, front contact 38 of relay 10-12, polar contact 39 of relay 10-12 in a right hand position, front contact 79 of relay 7T, to the control relay of signal 10B, which in turn clears signal 10B.

The clearing of signal 10B illuminates the indicator light 10SK located in the entrance button 10N informing the operator that the route has been completely set up and the signal cleared.

In a similar manner, the operator may set up a route between signals 13 and 14 by operating entrance button 13N in a clockwise direction and pressing exit button 14X thus closing a 75 circuit for energizing route relay 13-14 from

(+), through a circuit including contact 20 of switch SW in position M, front contact 40 of button 13N, back contact 41 of relay 10-11, winding of relay 13-14, back contact 42 of relay 10-12, back contact 50 of button 14N, back contact 43 of button 14X, contact 25 of switch SW in position M, to (-). The picking up of relay 13-14 closes a stick circuit from (+), through a circuit including contact 20 of switch SW in position M, front contact 40 of button 13N, back contact 41 of relay 10-11, winding of relay 13-14, back contact 42 of relay 10-12, polar contact 43 of relay 13-14 in a right hand position, front contact 44 of relay 13-14, contact 25 of the switch SW in position M, to (-).

The relay 13-14 being picked up energizes the circuit for the control of signal 13 from (+), through a circuit including front contact 45 of relay 13-14, polar contact 46 of relay 13-14 in a right hand position, to the control relay 20 (not shown) of signal 13 which in turn clears signal 13.

From the above description, it will be noted that the route relays are electrically interlocked so that only one route relay may be energized 25 at any time, the control of each relay being selected through back contacts of all the route relays for opposing or conflicting routes. These interlocking contacts are included in both the pick up and stick circuits of the route relays. 30

Having thus described in detail the operation of the system under manual control for routes set up from east to west and north to south, it is to be understood that a similar operation occurs in setting up routes for traffic from west to east 35 and south to north, the route relay circuits being the same in each case only energized with the opposite polarity, so that proper selections for the signals are made through the polar contact of the route relays in opposite positions. 40

Assuming the traffic conditions to be such that the control of the interlocking system by an operator is no longer required, the operator transfers the system to automatic operation by actuating the transfer switch SW to position A, first 45 checking the control panel to see that the track occupancy lamps are dark and that no routes have been set up by means of the entrance and exit buttons.

Under both automatic and manual operation 50 the same route relays are used and the same switch and signal control circuits are employed. The transfer switch determines whether the energy for the route relays is to be applied through the control buttons under manual operation or 55 through the contacts of the approach relays under automatic operation. In other words, the approach relays AR and ASR are used to take the place of the control buttons when the interlocking system is under automatic control. The 60 route relays are interlocked in such a way as to permit the relays for no two conflicting routes to be energized at the same time, the same as under manual operation. If a condition should exist that the approach sections on two conflicting 65 routes should become occupied at the same time, although the route relays for both routes try to pick up, the difference in the characteristics of the relays would allow one to gain preference over the other in a very short interval of time. 7b

Assuming a train to approach signal 10 on track 18, the dropping of track relay 2T energizes the approach relay 10AR, from (+), through a circuit including back contact 51 of relay 10S, back contact 52 of relay 2T, back contact 53 of 75

relay 12AR, back contact 54 of relay 11AR, contact 55 of push button 10-12PB in its normal position, back contact 56 of relay 10ASR, winding of relay 10AR, contact 57 of switch SW in position A, to (-).

Having picked up the approach relay 10AR, a circuit is closed for energizing route relay 10-11 from (+), through a circuit including contact 20 of switch SW in position A, front contact 58 of relay 10AR, winding of relay 10-11, back contact 22 of relay 13-14, back contact 23 of relay 10-12, front contact 59 of relay 10AR, contact 25 of switch SW in position A, to (-).

Having thus picked up route relay 10-11, the positioning of the switch and clearing of signal 10A will take place in a manner the same as previously described when the interlocking system was under manual control.

When using the approach sections at the opposite ends of a route as a means of automatically setting up that route and determining the direction of traffic in it, a means must also be provided whereby a train leaving the route and dropping the approach track relay on the leaving end of the route will not set up that route for a train movement in the opposite direction. Such a condition, of course, would prevent the setting up of other routes by trains approaching such other routes.

A relay S is associated with each signal and energized whenever a route relay sets up traffic opposing such signal, and is maintained energized by a stick circuit closed until the train has left the interlocking plant. This relay S for a signal prevents the approach section for such signal from being effective when a train is moving against such signal.

For example, with route relay 10-11 picked up a circuit is closed for energizing relay 11S from (+), through a circuit including front contact 60 of relay 10-11, polar contact 61 of relay 10-11 in a right hand position, winding of relay 11S, to (-).

The train accepting signal 10A drops track relay 7T which in turn closes a stick circuit for relay 11S from (+), through a circuit including front contact 62 of push button 11PB, back contact 63 of relay 7T, front contact 64 of relay 11S, winding of relay 11S, to (-).

The dropping of the track relay 7T also opens the control of signal 10A thus causing the green lamp to be extinguished and the red lamp to be illuminated.

When the train leaves track section 2, relay 10-11 is deenergized due to the opening of the circuit at front contacts 58 and 59 of approach relay 10AR, which in turn has been deenergized by the opening of back contact 52 of relay 2T.

As the train proceeds through the route and drops track relay 3T the circuit is held open for the control of relay 11AR at back contact 65 of relay 11S, which relay 11S is maintained picked up with relay 3T down by a circuit closed from (+), through a circuit including front contact 62 of push button 11PB, back contact 66 of relay 3T, front contact 64 of relay 11S, winding of relay 11S, to (-).

When the train leaves track section 3, the system of course restores to normal conditions.

Assuming a train on track section 2 desires to go over the route to track 17, a trainman operates the push button 10-12PB, which is located near signal 10, to thereby release the through route on track 18 which has already been set up, and to set up the desired diverging

route. This is done by dropping the approach relay 10AR and picking up the approach relay 10ASR, thus in turn dropping route relay 10-11 and picking up route relay 10-12. Relay 10AR is deenergized through the opening of front contact 55 of push button 10-12PB, while the circuit for the control of relay 10-11 is opened at front contacts 58 and 59 of relay 10AR.

The relay 10ASR is energized when the push button 10-12PB is pressed through a circuit closed from (+), including back contact 51 of relay 10S, back contact 52 of relay 2T, back contact 53 of relay 12AR, back contact 54 of relay 11AR, back contact 55 of push button 10-12PB, back contact 67 of relay 10AR, winding of relay 10ASR, contact 57 of switch SW, to (-). As soon as relay 10ASR picks up a stick circuit is closed for shunting out push button 10-12PB from (+), through a circuit including back contact 51 of relay 10S, back contact 52 of relay 2T, back contact 53 of relay 12AR, back contact 54 of relay 11AR, front contact 68 of relay 10ASR, winding of relay 10ASR, contact 57 of switch SW, to (-).

Relay 10ASR being picked up applies energy to route relay 10-12 by a circuit closed from (+), through a circuit including contact 20 of switch SW in position A, front contact 69 of relay 10ASR, back contact 33 of relay 10-11, back contact 34 of relay 13-14, windings of relay 10-12, front contact 70 of relay 10ASR, contact 25 of switch SW in position A, to (-). Relay 10-12 in a picked up position governs the control of signal 10B and track switch TS through the same circuits, as previously described.

When signal 10B clears after the operation of the track switch TS to a reverse position, the train proceeds over the route in the usual way. It is of course understood that relay 12S acts in the same manner as already described for relay 11S.

As approach relay 10ASR is held in its energized position through its stick circuit which is dependent upon contact 52 of relay 2T the same as approach relay 10AR, the relay 10ASR will drop as soon as track relay 2T picks up, thus releasing the approach relays for conflicting routes which were electrically interlocked by relay 10ASR being in its energized position.

It is evident that the dropping of relay 10ASR will allow the next train approaching on section 2 to automatically set up a through route on track 18, in the usual way. In other words, the actuation of the push button 10-12PB while a train is on section 2, is effective to set up the diverging route only for that train.

A train approaching signal 13 on track 19 and dropping track relay 5T energizes route relay 13-14, if all conflicting route relays are down.

More specifically, the dropping of relay 5T closes a circuit for energizing relay 13AR from (+), through a circuit including back contact 71 of relay 13S, back contact 72 of relay 5T, back contact 73 of relay 14AR, winding of relay 13AR, contact 57 of switch SW in position A, to (-).

Relay 13-14 is now energized from (+), through a circuit including contact 20 of switch SW in position A, front contact 74 of relay 13AR, back contact 41 of relay 10-11, winding of relay 13-14, back contact 42 of relay 10-12, front contact 75 of relay 13AR, contact 25 of switch SW in position A, to (-).

Relay 13-14 effects the clearing of signal 13 as heretofore described when the interlocking plant

was under manual control, so that the train can proceed over the route as usual.

Having thus described in detail circuits for train movement from east to west and north to south, it is evident that operation for the reverse directions is similar, using the same circuits with the opposite polarity applied to the route relays, and using the approach relays AR and stick relays S to accomplish that automatic control.

10 Each signal has associated therewith a push-button PB for dropping the associated stick relay S in cases where a train desires to reenter the interlocking plant while the system is under automatic operation. Each push button is located 15 near its signal so as to be readily accessible to a trainman.

For example, an east bound train having passed through the interlocking plant from the track section 7 into the track section 3, may set up a west bound route by pressing the push button 11PB. This causes the stick circuit of relay 11S to be opened at front contact 62 of push button 11PB, which in turn drops relay 11S to close the circuit for energizing approach relay 11AR at back contact 65 of relay 11S, thus allowing a route to be set up in the same manner, as under normal operation, by the closed condition of back contact 78 of relay 3T.

Having described one form of a traffic controlling system for railroads as one specific embodiment of the present invention, it is desired to be understood that this form is selected to facilitate in the disclosure of the invention rather than to limit the number of forms which it may assume; and, it is to be further understood that various modifications, adaptations and alterations may be applied to the specific form shown to meet the requirements of practice, without in any manner departing from the spirit or scope of the present 40 invention except as limited by the appended claims.

What I claim is:

1. In a traffic controlling system for railroads, a track layout having a plurality of conflicting 45 routes, signals for governing traffic over said routes, an approach section for each of said routes, a route relay for each of said routes, automatic means for energizing each particular route relay when a train occupies said approach section for that route providing said automatic means is rendered effective, manually operable means for energizing each particular route relay providing said manually operable means is rendered effective, a contactor for at times rendering effective said automatic means and at other times rendering effective said manually operable means, circuit means for interlocking said route relays so as to allow only one of said route relays to be energized at any one time, and circuit means for 50 clearing the signal for each particular route when said route relay for that route is energized.

2. In a traffic controlling system for railroads; a track layout having a plurality of conflicting routes; signals for governing traffic over said routes; an approach section for each of said routes; a route relay for each of said routes; automatic means for energizing each route relay when a train occupies its respective approach section providing said automatic means is rendered effective; a manually controlled button for the entrance end of each route; a manually controlled button for the exit end of each route; control means responsive, when rendered effective, to the joint operation of said entrance button and said exit button for any particular route

for energizing said route relay for that particular route; a manually operable contactor for at times rendering said route relays responsive to said automatic means and at other times rendering said route relays responsive to said control means; 5 circuit means for allowing only one of said route relays to be energized at any one time; and circuit means responsive to the operation of each of said route relays for energizing the signal for that route. 10

3. In a traffic controlling system for railroads; a track layout having two stretches of track connected by a track switch to thereby form two routes, a power operated switch machine for operating said track switch, signals for governing traffic over said routes, an approach track section for each route, a route relay for each route, automatic means for energizing each route relay when a train occupies the approach section for that particular route providing said automatic means is rendered effective, manually operable means for energizing each route relay providing said manually operable means is rendered effective, contact means for at times rendering said route relays responsive to said automatic means 20 and at other times rendering said route relays responsive to said manually operable means, circuit means for allowing the energization of only one route relay at any one time, circuit means responsive to the operation of said route relays 25 for controlling said switch machine to set up the route corresponding to the particular route relay then energized, and circuit means responsive to the operation of said route relays and said track switch for controlling said signals. 30

4. In a traffic controlling system for railroads, a track layout having a first stretch of track crossed by a second stretch of track, signals for governing traffic in both directions over each track, an approach section for each signal, a route relay for each track, automatic means for at times distinctively energizing said route relay in accordance with whether a train occupies one or the other of said approach sections for that track, a manually operable means for at other times distinctively energizing each route relay, manually operable contact means for determining which times said automatic means and said manually operable means are to be respectively rendered effective, circuit means for allowing only one route relay to be distinctively energized at any one time, a detector track section having a track relay, and circuit means for selecting and controlling the signal for each track responsive only to the distinctive energization of the route 50 relay for that track and the condition of said track relay. 55

5. In an interlocking system for railroads; a track layout having a plurality of conflicting routes; certain ones of which include at least one track switch; signals for governing traffic over said routes; an approach track section for each of said routes; a route relay for each of said routes; circuit means associated with each approach track section and rendered effective by a train in such section to energize its route relay, said means allowing only one of said route relays to be energized at a time; means for controlling said track switch to a proper position for each route over it when the route relay for that route is energized; 60 and means for clearing the signal for each route when its route relay is energized, said means acting to clear the signal for a route over said track switch only when said track switch is in a proper position for that route. 65

6. In an interlocking system for railroads; a first stretch of track crossed by a second stretch of track, signals governing traffic in both directions over each stretch of track, approach track sections in approach to each said signals, a route relay for each track, automatic means responsive to a train for energizing that one of said route relays corresponding to the approach track section for that track which is occupied by a train, means allowing only one of said route relays to be energized at a time, a lockout means for preventing the approach track section for a particular track from being effective to energize a route relay when that route is occupied by a train leaving the route, a manually operated means for at times rendering said lockout means ineffective, and a means for controlling said signals responsive to the operation of said route relays.

7. In an interlocking system for railroads; a track layout having a plurality of conflicting routes; signals for governing traffic over said routes; an approach track section for each of said routes, certain of said approach sections being common to two routes; a route relay for each of said routes; circuit means responsive to the presence of a train for energizing each route relay when its said approach track section is occupied, said means allowing only one of said route relays to be energized at a time; manually operated means for energizing a second of two route relays when the first relay has been automatically energized providing that the occupied approach section is common to both routes, said means effecting the deenergization of said first route relay; and means for clearing the signal for each route when its route relay is energized.

8. In an interlocking system for railroads, a first stretch of track crossed by a second stretch of track, signals governing traffic in both directions over each stretch of track, approach track sections in approach to each of said signals, a route relay for each track, automatic means for energizing a given route relay when either of the approach track sections for that track is occupied by a train, means allowing only one of said route relays to be energized at a time, lockout means for preventing the approach track section for a particular track from being effective to energize its route relay when that route is occupied by a train leaving the route, and means for clearing the signal for one direction or the other for a particular stretch of track when its route relay is energized depending upon whether such route relay is energized in response to the occupied condition of one approach track section or the other, whereby a train automatically causes the clearing of a signal upon approach to that signal and can pass through the route established thereby without clearing the signal for the opposite direction.

9. In an interlocking system for railroads, a first stretch of track crossed by a second stretch of track, signals governing traffic in both directions over each stretch of track, approach track sections in approach to each of said signals, a route relay for each track, automatic means for energizing each route relay when either of the approach track sections for that track is occupied by a train, means allowing only one of said route relays to be energized at a time, lockout means for preventing the approach track section for a particular track from being effective to energize its route relay when that route is occupied by a train leaving the route, means for clearing the signal for one direction or the other

for a particular stretch of track when its route relay is energized depending upon whether such route relay is energized in response to the occupied condition of one approach track section or the other, whereby a train automatically causes the clearing of a signal upon approach to that signal and can pass through the route established thereby without clearing the signal for the opposite direction, manually operable means associated with each of said approach track sections for at times rendering its lockout means ineffective, whereby a train after having passed through a route, may re-enter that route in the opposite direction.

10. In an interlocking system for railroads; a track layout having two conflicting routes interconnected by a track switch; signals for governing traffic over said routes; an approach track section common to both said routes; a route relay for each of said routes; circuit means controlled by a train on said common approach track section for energizing a particular one of said route relays when said approach track section is occupied; manually operable means for at times deenergizing said one route relay and energizing the other; means for controlling said track switch to a proper position for each route over it when the route relay for that route is energized; and means for clearing said signals for said routes when their corresponding route relays are energized.

11. In a traffic controlling system for railroads; a plurality of tracks forming a plurality of conflicting routes, signals governing traffic in both directions over each route, a route relay for each route, automatic means responsive to the presence of a train for energizing each route relay with one polarity or the other in accordance with whether a train approaches one signal or the other governing traffic over the corresponding route, said automatic means being effective only when all conflicting route relays are deenergized, and means responsive to the polarity of energization of each route relay for selecting the signal to be cleared for its route.

12. In a traffic controlling system for railroads; a track layout having a plurality of conflicting routes; signals for governing traffic over said routes; an approach section for each signal; route establishing means for each of said routes for setting up its respective route and clearing a signal governing traffic thereover when actuated; automatic means for actuating said route establishing means when a train occupies the approach section to that route providing said automatic means is rendered effective; control buttons for the opposite ends of each of said routes; means responsive to the joint operation of the control buttons for the opposite ends of each route for actuating said route establishing means for that route providing said control buttons are rendered effective; means for at times rendering said automatic means effective and at other times rendering said control buttons effective; and circuit means for allowing only one of said route establishing means for said conflicting routes to be actuated at the same time.

13. In a traffic controlling system for railroads, a track layout having a plurality of conflicting routes, signals located at the opposite ends of each route for governing traffic over said routes in both directions, an approach track section for each of said signals, a route relay for each of said routes, a manually operable contactor capable of assuming either of two positions, auto-

matic means responsive to the presence of a train on one or the other of the approach track sections at the opposite ends of a route for energizing the route relay for the intervening route with one polarity or the other, said means being rendered effective only when said manually operable contactor is in one of its two positions, manually operable control buttons for the signal locations constituting the entrance and exit ends of said routes, circuit means responsive to the joint operation of the entrance and exit control buttons for a given route for energizing

the associated route relay with the particular polarity to clear the signal at the entrance end of that route, said circuit means being rendered effective only when said manually operable contactor is in the other of its two positions, circuit means for allowing only one of said route relays to be energized at any one time, and a signal control circuit for each signal rendered effective to clear such signal when the route relay for the route over which it governs traffic is energized with the proper polarity.
